The present application is a continuation of my pending application, Serial No. D. 17,278, filed on November 5, 1951 for a Stackable Chair, now abandoned.

Fig. 1 is a front perspective view of a stackable chair showing my new design.

Fig. 2 is a rear perspective view thereof on a smaller scale.

Figs. 3, 4 and 5 are front, side and rear elevational views, respectively, of the stackable chair.

Fig. 6 is a top plan view thereof.

I claim:

The ornamental design for a stackable chair, substantially as shown.
